UNITED STATES PATENT OFFICE.

JONAS NORTHRUP, OF HOPE DALE, MASSACHUSETTS, ASSIGNOR TO HOPE DALE MANUFACTURING COMPANY, OF MILFORD, MASSACHUSETTS, A CORPORATION OF MASSACHUSETTS.

SHUTTLE.

1,280,819.

Specification of Letters Patent.

Patented Oct. 8, 1918.

Application filed October 30, 1916. Serial No. 128,483.

To all whom it may concern:

Be it known that I, JONAS NORTHRUP, a citizen of the United States, residing at Hopedale, in the county of Worcester and State of Massachusetts, have invented certain new and useful Improvements in Shuttles; and I do hereby declare the following to be a full, clear, and exact description of the invention, such as will enable others skilled in the art to which it appertains to make and use the same.

This invention relates to self-threading shuttles of the type employed in automatic weft-replenishing looms.

In shuttles of the type in question it is common to employ a threading-device having means by which the thread is automatically directed into a longitudinal thread-passage near the end of the shuttle, and from thence through an eye in the forward surface of the shuttle. In passing from the thread-passage to the eye the thread makes an angle, so that a guiding-device of some sort is necessarily provided, around which the thread is drawn and deflected at this point. This thread-guide is subjected to wear, owing to the friction of the thread against it, and it is therefore common to employ wear-resistant material, such as porcelain or glass, in the construction of the thread-guide.

The object of the present invention is to improve and simplify the means by which a wear-resistant thread-guide is provided at the point above indicated, and to this end the invention consists in the construction hereinafter described, as it is defined in the appended claim.

In the accompanying drawings Figures 1 and 2 are, respectively, a plan-view and a front-elevation of the forward portion of a shuttle embodying the present invention, and Figs. 3, 4 and 5 are, respectively, a front-elevation, an end-elevation, and a bottom plan-view of the threading-device of the shuttle.

The invention is illustrated as embodied in a shuttle having the general characteristics of self-threading shuttles as well known in the art. The wooden body 6 of the shuttle is recessed, at the forward end, to receive a metal threading-device 7, this de-

vice being shown as formed by a single integral casting. The body-portion 8 of the threading-device is sunk deeply into a recess in the shuttle-body, and is secured in place by a bolt 9 in the usual manner. The threading-device is provided with means, including a beak 10 and a horn 11, for guiding the thread into the thread-delivering eye 12 and for preventing its accidental escape. The threading-device is also provided with the usual thread-passage 13 extending longitudinally of the shuttle.

Upon emerging from the forward end of the thread-passage 13 the thread turns at a right-angle, so as to issue through the eye 12. The thread-guiding device in which the present invention resides is employed at this point. For this purpose the threading-device is provided with an integral downwardly-projecting portion 14, which is located at the forward extremity of one of the side-walls of the body 8 and is shown as constituting a portion or a continuation of said side-wall. In this member 14 a vertical bore 15 is produced, this bore extending downwardly from the upper surface of the threading-device, and terminating short of the lower extremity of the member 14 so that the lower end of the bore is closed. The metal of the member 14 is also cut away, at the front, so as to provide a recess 16 opening into the bore 15.

The thread-guide is in the form of a cylindrical rod 17 of wear-resistant material, such as glass, and this rod is introduced into the bore 15 through the open upper end thereof, and is fixed in the bore, either by close fitting or by the use of cement or other retaining-means. Through the recess 16 the surface of the thread-guide 17 is exposed for engagement with the thread.

The thread-guide is so embraced by the metal of the member 14 that it is effectually protected against any strains tending to break it. Owing to the fact that the bore 15 is open only in an upward direction the thread-guide is retained in its place by the action of gravity, even in case it becomes loose in the bore. The invention, in addition to these advantages, has the further advantage of being simple and inexpensive, being well adapted for integral construction.

of the threading-device, and it has other advantages which will be apparent to those skilled in the art.

What is claimed is:

5 A self threading shuttle for automatic looms having a delivery eye in its thread delivery end, and being provided with a threading device comprising a thread passage leading into the delivery eye, a down-
wardly projecting member integral with the

threading device and located at the junction of the thread passage and the delivery eye, said threading device provided with a vertical bore extending from the top thereof and partly through said member, a recess in the 15 member opening from the delivery eye into the bore, and a rod of wear-resisting material fixed in the bore and exposed through the recess for engagement by the thread.

JONAS NORTHRUP.
